UNITED STATES PATENT OFFICE

92,189

DESIGN FOR A DOUBLE DECK TRANSPORT AIRPLANE

Robert J. Minshall and Frank R. Canney, Seattle,
Wash., assignors to Boeing Airplane Company,
Seattle, Wash., a corporation of Washington

Application July 25, 1933, Serial No. 48,832

Term of patent 7 years

To all whom it may concern:

Be it known that we, ROBERT J. MINSHALL and FRANK R. CANNEY, both citizens of the United States, and both residing at Seattle, in the county of King and State of Washington, have invented a new, original, and ornamental Design for Double Deck Transport Airplanes, of which the following is a specification, reference being had to the accompanying drawing, forming part thereof.

Figure 1 is a three-quarter top plan view in perspective of the airplane, showing our new design.

Figure 2 is a three-quarter front and bottom view in perspective, showing our new design.

Fig. 3 is a front elevational view of the airplane showing our new design.

The airplane has a wing joined to the cabin or fuselage between the top and bottom thereof, with windows provided both above and below the wing.

We claim:

The ornamental design for a double deck transport airplane, as shown and described.

Signed at Seattle, King County, Washington,
this 21st day of July, 1933.

ROBERT J. MINSHALL.
FRANK R. CANNEY.
